UNITED STATES PATENT OFFICE.

FREDERICK JOHN EDWIN CHINA, OF ESHER, ENGLAND.

EXTRACTING MATERIAL.

Application filed May 19, 1923. Serial No. 640,284.

To all whom it may concern:

Be it known that I, FREDERICK JOHN EDWIN CHINA, a subject of the King of Great Britain, residing at Esher, in the county of 5 Surrey, England, have invented certain new and useful Improvements in Extracting Materials, of which the following is a specification.

My invention relates to the extraction of 10 substances from solids, and it has been successfully employed in the pharmaceutical industry for the extraction of desired substances from meat and other animal tissues, as well as vegetable materials, such as 15 woods, barks, leaves, grasses, roots, tubers, and other such tissues.

An object of my invention is to provide a 20 method of extraction which will give a high percentage of the extractable substances in one short extracting operation.

Another object of my invention is to 25 show how to extract desirable substances from solid matter in a quick and economical operation.

A still further object of my invention is to 30 provide a system of extraction wherein the entire process is carried out continuously and in a closed circuit, whereby very volatile solvents may be employed without danger of their loss by evaporation.

In the methods heretofore used, extraction 35 has ordinarily been accomplished by subjecting the solid matter to any one of the following processes: (1) percolation; (2) maceration; (3) digestion; (4) distillation; or the combination of any or all of these. In such processes it is ordinarily necessary to subject the solid particles to successive re-treatments in order to secure a 40 satisfactory percentage yield of substances extracted, and even where re-treatment has not been necessary, the process has generally been a protracted operation. These methods have proved to be tedious and 45 costly.

Broadly speaking, my invention comprises subjecting the particles of solid matter to the forces at work within a film of solvent passing between surfaces moving past each other at a relatively high velocity. Though the exact theory of the action 50 is not fully determined, it is thought that the forces existing in such film cause a pumping of the liquid through the fibers or tissues of the solid. In other words, it is believed that the result obtained is accom-

plished by reason of an action similar to that which takes place within a sponge when alternately squeezed and allowed to expand under the surface of a liquid. The 60 action is such as to rapidly and repeatedly present fresh solvent to the whole of the fiber or tissue of the substance in question, so that no concentration of extractive in the solvent can occur on any portion of the 65 tissue or fiber. There appears to be a distinct pumping action throughout the whole structure.

In order to carry out my invention, I 70 have illustrated a machine in the accompanying drawings for carrying out my process, as will hereinafter be more particularly set forth.

In the drawings:

Figure 1 is a longitudinal cross sectional 75 view of my device taken through the axis of the rotor;

Fig. 2 is a cross sectional view taken on the line 2—2 of Fig. 1, looking in the direction of the arrows;

Fig. 3 is a detail view partly in section 80 illustrating a modification of my device in which the input chamber is made very small.

Referring to the drawings for a detailed description, I have shown an extracting mill 85 which comprises a base casting 1 adapted to be bolted to a suitable support (not shown) by means of a series of bolts 2. The casting 1 is formed with a lower annular flange 3 and an upper annular flange 4 through 90 which the bolts 2 that hold the device in place pass. Formed within the casting 1 is a fluid containing chamber 5 having an inlet pipe 6, and an outlet pipe 7 leading into the chamber and adapted to discharge at a 95 point near its top. The purpose of the inlet and outlet pipes is to allow either heating or cooling fluid, such as steam or cooling brine, to be circulated in the chamber 5 to either raise or lower the temperature at 100 which the extracting operation takes place.

Formed within the bottom portion of the casting 1 is an input duct 8 through which the comminuted solid substances and the solvent may be introduced by any suitable 105 means, such as a pipe (not shown). Formed in the upper part of the casting 1 is a conical surface 9 and between the conical surface 9 and the input duct 8 is comprised a frusto-conical input chamber 11. The conical surface 9 is preferably ground smooth.

Mounted on the casting 1 is a cover plate

12 which forms with the casting 1 an output chamber 13 from which an output duct 14 leads. A suitable valve 15 is provided for regulating the amount of material allowed to pass through the output duct 14. Thus the time during which the material is acted upon by the mill can be regulated. The casting 1 is formed with an annular shoulder 16 at its top, and the cover plate 12 is provided with an annular groove 17 in which the shoulder 16 of the casting 1 fits. Between the groove 17 and the shoulder 16 I insert suitable packing material 18.

The cover plate 12 is provided with an annular flange 19 which overlies the annular flange 4 of the casting 1. The bolts 2 which hold the casting 1 to the support pass through the flange 19, as well as the flanges 3 and 4 of the casting 1, and hold the cover plate firmly in place. For purposes of carefully adjusting the relative position of the cover plate 12 to the casting 1, I have provided a series of wedges 21, one of which is shown in Fig. 1. The wedges are adapted to lie between the bolts 2 and in practice I have found that three wedges will enable good adjustment to be made. By means of these wedges, a careful adjustment of the relative position of the cover plate 12 to the casting 1 may be made, in order to properly center the working parts.

Mounted on top of the casting 1 is a supporting structure 22. The supporting structure 22 is provided with a flange 23 at its lower end which is adapted to lie in contact with the top of the cover plate 12. The inner periphery of the flange 23 of the support piece is adapted to abut against an annular shoulder 24 formed on the cover plate 12. A series of holding bolts 25 hold the support member 22 in position. The support member 22 has preferably integrally formed therewith upwardly extending support spiders 26 which terminate at their upper extremity in a ring member 27, the interior surface of which is screw-threaded, as indicated at 28.

A bearing support piece 29 is provided on its downwardly extending annular portion 31 with screw-threads 32 which are adapted to engage with the screw-threads 28 of the ring member 27, permitting the bearing support 29 to be adjustable. A lock nut 33 is provided to lock the bearing support 29 in any adjusted position, and a pointer 34 is provided to co-operate with a scale on the periphery of the bearing support to indicate its relative adjustment.

My extracting mill is provided with a conical rotor 35 having a smooth conical surface 36 adapted to lie adjacent the smooth conical surface 9 of the casting 1. The rotor 35 is mounted on a shaft 37 and held securely on the shaft by means of a nut 38. On the upper end of the shaft 37 are screw-

threads 39 upon which are adapted to be screwed locking nuts 41. Below the screw-threads 39 the shaft 37 has a slightly enlarged portion 42 over which is adapted to fit an inner upper ball race 43. An outer upper ball race 44 is adapted to fit in a cylindrical aperture 45 formed in the bearing support 29. Between the inner and outer ball races are two series of balls 46.

Below the portion 42 the shaft is slightly enlarged, as indicated at 47, and around the upper part of the portion 47 of the shaft is fitted a collar 48, whose upper end contacts with the upper inner ball race 43. The bearing support 29 is provided with an inwardly extending annular shoulder 49 having annular packing glands 51 therein, in which is packed suitable packing to prevent leakage of lubricant from the bearing. A journal box cover 52 is bolted by means of bolts 53 to the bearing support 29. The journal box cover 52 has a downwardly projecting annular lip 54, which holds the upper outer ball race 44 firmly between the annular lip 54 and the shoulder 49 formed on the bearing support member 29.

The bearing structure comprising the inner and outer upper bearing races and the balls, operates as a thrust and radial bearing.

On the portion 47 of the shaft 37 is a drive pulley 55 which is keyed to the shaft. The cover plate 12 is provided with an annular recess 56 within which is mounted the lower bearing and packing structure which I will now describe. Mounted on the portion 47 of the shaft extending below the pulley 55 is a collar 57, whose upper end is adapted to engage the lower end of the pulley 55. The collar is mounted within a packing gland 58 comprising a plate 58 which lies over the upper end of the annular recess 56, and is bolted by means of bolts 59 to the upper side of the cover plate 12. The plate 58 is provided with two annular recesses 61 on its inner periphery within which is placed a suitable packing to form a tight packing joint around the collar 57.

Mounted below the collar 57 on an enlarged portion 62 of the shaft 37 is an inner ball race 63, whose lower end rests against the shoulder formed between the portion 62 of the shaft and an enlarged lower portion 64 of the shaft. The upper portion of the inner ball race 63 is in contact with the lower portion of the collar 57. Arranged to slidably fit within the walls of the annular recess 56 is an outer ball race 65. Between the inner and outer ball race are series of balls 66. To prevent leakage of lubricant through the lower opening of the annular recess 56 through which the portion 64 of the shaft 37 passes, I have formed the annular recess 56 with an inwardly projecting annular shoulder 67. Below the shoulder 67

67 the inner walls of the recess 56 are inwardly tapered at 68, to the point at which the portion 64 of the shaft 37 passes through the lower part of the cover plate 12.

5 Fitting around the portion 64 of the shaft is a packing plate 69 having a shoulder 71, lying above the shoulder 67 of the cover plate 12, with its outer periphery in engagement with the inner periphery of the 10 annular recess 56. The packing plate 69 is formed with a downwardly extending lip 72, which fits around the portion 64 of the shaft 37. Between the lower edge of the downwardly extending lip 72 and the sloped 15 walls 68 in the cover plate, I have inserted packing material 73 to prevent leakage of lubricant.

To hold the packing plate 69 pressed against the packing 73, I have formed an 10 annular groove 74 in the wall of the recess 56. Within this groove I mount a split ring 75 whose elasticity when sprung into position keeps the packing plate 69 pressed against the packing 73. The packing gland 5 so formed is adapted to ordinarily withstand a pressure of about twenty-five pounds without leakage. This packing gland near the lower portion of the cover plate not only serves to prevent lubricant from leaking 20 out of the lower bearing structure, but at the same time provides means for preventing liquid within the output chamber of the mill from passing into the lower bearing, should any considerable pressure be 30 generated in this output chamber 13.

The adjustment of the clearance between the conical surface 9 and the conical rotating surface 36 of the rotor 35, can be 40 very easily and accurately effected by loosening the lock nut 33 on the threaded portion 31 of the bearing support 29, and rotating the bearing support 29 until the exact adjustment is obtained. The lock nut 33 is then screwed in place. The pointer 34 enables the person performing the adjustment 45 to accurately tell the degrees of rotation imparted to the bearing support 29. As before stated, the bearing support 29 is preferably formed with a scale on its outer periphery for co-operation with the pointer 34 to enable an accurate adjustment to be 50 obtained.

The whole upper bearing structure is either 55 raised or lowered by rotating the bearing support 29. The outer upper ball race 44 is moved with the bearing support and through the balls 45 carries the inner ball race 43 with it. The inner ball race is held 60 against longitudinal displacement on the shaft by the collar 48, whose lower end abuts the fixed pulley 55, and by the lock nuts 41. By reason of the fact that the lower inner ball race 63 is held against longitudinal 65 movement on the shaft by the shoulder formed between the portion 62 and 64 of the

shaft, and by the collar 57, the lower inner ball race 63 must move with the shaft. The balls 66 cause the outer ball race 65 to slide either up or down within the annular recess 56, in accordance with the adjustment of 70 the shaft.

It will be apparent by reason of the bearing mountings and the shaft structure that when the upper bearing support 29 is either raised or lowered, the lower bearing moves 75 with it.

One of the supports 26 is made of less 80 arcuate breadth than the other supports to permit a belt 76 to pass readily over the pulley 55. A suitable source of power moves the belt 76, which imparts rotation 85 to the pulley 55 to cause the rotor 35 to rotate. The screw-threads which are formed on the upper bearing support 29 are in such a direction, that the normal direction of 90 rotation of the belt 76 will cause the upper bearing support 29 to unscrew in case the lock nut 33 is not tightly adjusted to prevent such an occurrence. This gives an 95 added factor of safety, for should the proper tightening of the lock nut 33 not be effected, the normal operation of the machine will tend to continually increase the distance between the smooth conical working surfaces, thus preventing injury to the machine. 100

I have found that in extracting materials the clearance between the conical surface of the rotor and stationary conical surface 9 should be approximately thirty one thousandths ($\frac{3}{1000}$) of an inch or less. 105 The peripheral speed of the rotor may vary from approximately 200 feet a second to 500 feet a second, depending upon the operating conditions.

In Fig. 3 I have shown a modification of 110 my mill in which the input chamber 11 is materially reduced in size. Under certain conditions of operation, I have found a small input chamber to be advisable. The conical rotor revolving at high speed causes considerable suction in the input chamber 11 by reason of the centrifugal action on the liquid. This action causes the feeding of material through the mill, but where there 115 is a large input chamber, under certain conditions, a partial vacuum may be produced. The material is then fed in pulses, but where the input chamber is restricted in size, there is not so much danger of pulsation, since a 120 large quantity of the liquid cannot be evacuated from the input chamber at one time. Under certain working conditions, the modification shown in Fig. 3 has been found the preferred form in practice. 125

In operation, the material from which the 130 desired substance to be extracted is introduced into the input chamber of the mill, together with a suitable solvent therefor. The spacing apart of the conical stator and rotor surfaces of the machine is such that

the particles of solid matter from which the extraction is to be obtained may normally pass freely between these surfaces. It is convenient in practice to disintegrate the 5 bark, root, or other fiber to a size that will readily pass through a screen having from 40 to 60 meshes to the linear inch, though I do not wish to be limited in my disclosure to the exact size of the particles herein set 10 forth, which may vary with the various factors of the operation, such as, temperature, the material or solvent used, closeness of texture of the fiber or tissue, the size of the machine, and the speed at which it is 15 operated.

Certain types of relatively soft materials, of which meat is an example, do not have to be comminuted to a diameter that is equal to or less than the distance between the 20 relatively moving surfaces. By reason of their softness, particles of such materials deform to a sufficient extent to permit them to readily pass between surfaces, the distance between which is less than the normal 25 size of the particles treated. It has been found that even relatively large particles of substances of this class are not disintegrated to any substantial extent by my method of treatment.

30 The material having been thus suitably prepared, is suspended and kept roughly agitated in the solvent which is suitable for the particular extractive under treatment. The concentration of original solid matter 35 in the solvent will be varied to suit conditions, and may in general be within the limits of ten to thirty per cent. This factor is not important, because in many cases the percentage of extractive in the solid matter 40 may be very small, in which case the solution from the first process will be used to treat fresh solid in the next operation. In fact, under certain conditions, fresh solids 45 can be treated in a cycle of operations such as may be carried on in a battery system, but this procedure is usually not necessary.

The suspension of solid matter in the suitable solvent is now passed through the 50 mill under suitable conditions of temperature, relative velocity of moving faces, distance apart of moving faces, and pressure. It is found in practice that in almost every case complete extraction takes place under these optimum conditions, in one treatment. Under ordinary circumstances if the said 55 solid had been merely digested with the same solvent for a like period of time, a very low percentage extraction would have taken place. It is reasonable to suppose, therefore, that the treatment to which the 60 solid matter has been subjected in the film in the presence of the solvent, has in some manner forced the solvent rapidly through the structure of the solid matter.

65 The rapid motion of the solvent through

the fibrous structure has been so complete as to remove all the extractable matter within it, and this action is particularly remarkable when one considers that the solid matter has only been subjected to this action within the film for a very small fraction of a second. The forces existing between the relatively moving surfaces are believed to be of such a nature that the solvent is caused almost instantaneously to penetrate every part of the structure of the solid treated. As at first stated, it is believed that there is a pumping action existing in the film, whereby the solid particles in their passage between the surfaces have 75 all portions of their interior structure subjected many times to fresh batches of the solvent.

The forces causing this action are not, it is believed, due to the centrifugal action 80 within the film but rather to the shearing action between the surfaces moving past each other at a high velocity. The optimum conditions of the treatment are such that the speed of the relatively moving surfaces 85 and the thickness of the film do not tend to cause any actual disintegration of the particles within the film, but are only sufficient to cause this high speed pumping of solvent 90 through the particles in question. 95

Example 1.—Commercial ginger is previously prepared by grinding so that it will pass through a sieve having forty spaces to the linear inch. Approximately three or less pounds of the prepared ginger 100 are then stirred up in each gallon of water, preferably at a temperature of from fifty to seventy degrees centigrade. This mixture is then run through the mill, which has previously been adjusted to have a 105 clearance between the relatively movable surfaces of twenty-five to thirty one-thousandths of an inch. The speed is arranged so that the relative velocities of the adjacent surfaces of the mill is approximately 200 110 feet per second. The rate of flow of such a mixture can conveniently be adjusted to about five or six gallons per hour, and under these conditions the energy absorbed will be approximately 10 horse power. 115

The resulting mixture will contain the ginger from which practically all of the ginger extract has been removed, together with the liquid containing the liquid extract. If a little of the residual ginger be taken 120 and simply washed with water to remove the adhering ginger solution, it will be found that extraction has been so complete as to leave practically no taste of ginger in the solid. This complete extraction is readily obtained by passing the liquid once only through the mill.

Example 2.—A typical commercial cinchona bark may be treated as follows:

The bark is first disintegrated to pass 125

5 a mesh of forty to the linear inch. It is then dried and mixed with a requisite quantity of lime in order to liberate the crude quinine bases from their original state of combination as tannates. A suitable solvent, such as coal tar naphtha containing five per cent of fusel oil is now stirred up with from one to three pounds of prepared bark per gallon of solvent. The 10 resulting mixture is passed through the mill under the same conditions as given in the previous example. The temperature, however, need be but thirty to forty degrees centigrade. It will be found that practical- 15 ly complete extraction of the cinchona bark has taken place after one operation and that substantially the whole of the crude bases are in solution in the solvent. The 20 practical point to notice in this process is that very little coloring matter is removed from the bark in the short time of treatment, and in general it will be found that the crude bases are only a very pale buff color in appearance. This assists materially 25 in producing a pure white quinine free from color, and makes the expense of refining the product extremely small.

Practically the same conditions of treatment apply in general to the extraction of 30 such materials as quebracho, *hyoscyamus muticus*, *cascara sagrada*, *coco*, and *Mimosa* bark; the correct solvents, of course, being used in each case, such solvents being exactly the same as are now used in existing commercial processes.

Example 3.—The process is particularly useful in extracting animal fibers, such as meat, as it enables one to extract everything, including albuminoids, in the cold. The 40 meat is disintegrated to a suitable size and mixed with water in the proportions of approximately two pounds of meat to the gallon of water, to which may be added such aids to extraction as glycerine, salt, etc. The 45 resulting mixture is passed through the mill under suitable conditions, depending on the structure of the actual meat fiber. It will be found that on passing the meat once or twice through the mill, a complete extraction will have taken place and the resulting meat fiber remains as a pinkish white slime.

In the same manner, extracts from animal 50 organs giving pancreatic juices, pepsin, insulin, cantharides (from Chinese or Spanish cantharides fly) thyroid extracts, etc., may be obtained.

I have accomplished the extraction of desired substances from solid matter by utilizing the forces set up within a film of solvent, containing the solid matter, existing 55 between closely adjacent surfaces moving past each other at high velocity. The forces set up are such as to almost instantaneously cause the solvent to penetrate the entire mass

of the solid treated and to thoroughly cleanse the fibers of the soluble substances. It is believed that the solids are subjected to a rapid series of pumping actions whereby successive fresh and unsaturated portions of 70 the solvent are brought repeatedly into contact with the fibers of the solid substance.

While I have shown and described the preferred embodiment of my invention, I 75 wish it to be understood that I do not confine myself to the precise details of construction herein set forth, by way of illustration, as it is apparent that many changes and variations may be made therein, by those skilled in the art, without departing 80 from the spirit of the invention, or exceeding the scope of the appended claims.

I claim:—

1. A method of obtaining an extract from a solid substance comprising, passing the solid substance together with a suitable solvent of the material to be extracted in a thin film between surfaces relatively movable one past the other at high velocity, whereby the 85 solvent is washed through the fibers of the solid and an extract of material obtained, the velocity of movement of the surfaces past each other and the thickness of the film being such that the solid is not wholly disintegrated. 90

2. A method of obtaining an extract from a solid substance comprising, passing the solid substance together with a suitable solvent of the material to be extracted in a thin film between surfaces relatively movable one past the other at high velocity, whereby the solvent is washed through the fibers of the solid and an extract of material obtained, the velocity of movement of the 95 surfaces past each other and the thickness of the film being such that the solid is not wholly disintegrated to any substantial extent. 100

3. A method of obtaining an extract from a solid substance comprising, passing the comminuted solid substance together with a suitable solvent of the material to be extracted in a thin film between surfaces separated by a distance greater than the size of the comminuted solid particles, and relatively movable one past the other at high velocity, whereby the solvent is washed through the fibers of the solid and an extract of material obtained, the velocity of movement of the surfaces past each other and the thickness of the film being such that the solid is not wholly disintegrated. 110

4. A method of obtaining an extract from a solid substance comprising, passing the comminuted solid substance, together with a suitable solvent of the material to be extracted, in a thin film between surfaces separated by a distance greater than the size of the comminuted solid particles, and relatively movable one past the other at high velocity, whereby the solvent is washed 115 through the fibers of the solid and an extract of material obtained, the velocity of movement of the surfaces past each other and the thickness of the film being such that the solid is not wholly disintegrated. 120

through the fibers of the solid and an extract of material obtained, the velocity of movement of the surfaces past each other and the thickness of the film being such that 5 the solid is not disintegrated to any substantial extent.

5. A method of obtaining an extract from relatively soft substances comprising, passing the comminuted substances, together 10 with a suitable solvent of the material to be extracted, in a thin film between surfaces which may be separated by a distance less than the size of the comminuted particles and relatively movable one past the other at high velocity, whereby the solvent is washed through the fibers of the solid and an extract of material obtained, the velocity of movement of the surfaces past each other and the thickness of the film being such that 15 to any substantial extent.
10. A method of obtaining an extract from a solid comprising, passing the solid substance, together with a suitable solvent of the material to be extracted, in a thin film between smooth, equi-distantly spaced surfaces relatively movable one past the other at high velocity, whereby the solvent is washed through the fibers of the solid and 85 an extract of material obtained, the velocity of movement of the surfaces past each other and the thickness of the film being such that the solid is not disintegrated to any substantial extent. 90

6. A method of obtaining an extract from relatively soft substances comprising, passing the comminuted solid substances, together with a suitable solvent of the material to be extracted, in a thin film between surfaces which may be separated by a distance less than the size of the comminuted particles, and relatively movable one past the other at high velocity, whereby the solvent is washed through the fibers of the solid and an extract of material obtained, the velocity of movement of the surfaces past each other and the thickness of the film being such that the solid is not disintegrated to 25 any substantial extent. 100

7. A method of obtaining an extract from a solid comprising, passing the solid substance, together with a suitable solvent of the material to be extracted, in a thin film 40 between smooth surfaces relatively movable one past the other at high velocity, whereby the solvent is washed through the fibers of the solid and an extract of material obtained, the velocity of movement of the surfaces past each other and the thickness of the film being such that the solid is not disintegrated to any substantial extent. 105

8. A method of obtaining an extract from a solid substance comprising, passing the comminuted substance, together with a suitable solvent of the material to be extracted, in a thin film between smooth surfaces separated by a distance greater than or equal to the size of the comminuted particles and relatively movable one past the other at 45 high velocity, whereby the solvent is washed through the fibers of the solid and an extract of material obtained, the velocity of movement of the surfaces past each other and the thickness of the film being such that the solid is not disintegrated to any substantial extent. 110

9. A method of obtaining an extract from relatively soft solid substances comprising, passing the comminuted solid substance, to- 55 60 65

gether with a suitable solvent of the material to be extracted, in a thin film between smooth surfaces which may be separated by a distance less than the size of the comminuted particles and relatively movable one past the other at high velocity, whereby the solvent is washed through the fibers of the solid and an extract of material obtained, the velocity of movement of the surfaces past each other and the thickness of the film being such that the solid is not disintegrated to any substantial extent.

11. A method of obtaining an extract from a solid substance comprising, passing the comminuted substance, together with a suitable solvent of the material to be extracted, in a thin film between smooth, equi-distantly spaced surfaces separated by a distance greater than or equal to the size of the comminuted particles and relatively movable one past the other at high velocity, whereby the solvent is washed through the fibers of the solid and an extract of material obtained, the velocity of movement of the surfaces past each other and the thickness of the film being such that the solid is not disintegrated to any substantial extent. 90

12. A method of obtaining an extract from relatively soft solid substances comprising, passing the comminuted solid substances, together with a suitable solvent of the material to be extracted, in a thin film between smooth, equi-distantly spaced surfaces separated by a distance which may be less than the size of the comminuted particles and relatively movable one past the other at high velocity, whereby the solvent is washed through the fibers of the solid and an extract of material obtained, the velocity of movement of the surfaces past each other and the thickness of the film being such that the solid is not disintegrated to any substantial extent. 100

13. A method of obtaining an extract from a solid substance comprising, passing the solid substance, together with a suitable solvent of the material to be extracted, in a thin film between surfaces relatively movable one past the other at a speed of from 200 to 500 feet a second, said surfaces being spaced apart a distance not greater than thirty one thousandths ($\frac{1}{3000}$) of an inch, 110 115 120 125

whereby the solvent is washed through the fibers of the solid and an extract of material obtained, the velocity of movement of the surfaces past each other and the thickness of the film being such that the solid is not disintegrated to any substantial extent.

14. A method of obtaining an extract from a solid substance comprising, passing the comminuted solid substance, together with a suitable solvent of the material to be extracted, in a thin film between surfaces separated a distance not greater than thirty one thousandths ($\frac{3}{1000}$) of an inch, the size of the comminuted solid particles being not greater than the spacing of these surfaces, said surfaces being relatively movable one past the other at a velocity of from 200 to 500 feet a second, whereby the solvent is washed through the fibers of the solid and an extract of material obtained, the velocity of movement of the surfaces past each other and the thickness of the film being such that the solid is not disintegrated to any substantial extent.

15. A method of obtaining an extract from relatively soft solid substances comprising, passing the comminuted solid substances, together with a suitable solvent of the material to be extracted, in a thin film between surfaces separated a distance not exceeding thirty one thousandths ($\frac{3}{1000}$) of an inch, which distance may be less than the size of the particles, said surfaces being relatively movable one past the other at a velocity of from 200 to 500 feet per second, whereby the solvent is washed through the fibers of the solid and an extract of material obtained, the velocity of movement of the surfaces past each other and the thickness of the film being such that the solid is not disintegrated to any substantial extent.

16. A method of obtaining an extract from a solid substance comprising, passing the solid substance, together with a suitable solvent of the material to be extracted, in a thin film between smooth surfaces relatively movable one past the other at a speed of from 200 to 500 feet a second, said surfaces being spaced apart a distance not greater than thirty one thousandths ($\frac{3}{1000}$) of an inch, whereby the solvent is washed through the fibers of the solid and an extract of material obtained, the velocity of movement of the surfaces past each other and the thickness of the film being such that the solid is not disintegrated to any substantial extent.

17. A method of obtaining an extract from a solid substance comprising, passing the comminuted solid substance, together with a suitable solvent of the material to be extracted, in a thin film between smooth surfaces separated a distance not greater than thirty one thousandths ($\frac{3}{1000}$) of an inch, the size of the comminuted solid par-

ticles being not greater than the spacing of these surfaces, said surfaces being relatively movable one past the other at a velocity of from 200 to 500 feet a second, whereby the solvent is washed through the fibers of the solid and an extract of material obtained, the velocity of movement of the surfaces past each other and the thickness of the film being such that the solid is not disintegrated to any substantial extent.

18. A method of obtaining an extract from relatively soft solid substances comprising, passing the comminuted solid substances, together with a suitable solvent of the material to be extracted, in a thin film between smooth surfaces separated a distance not exceeding thirty one thousandths ($\frac{3}{1000}$) of an inch, which distance may be less than the size of the particles, said surfaces being relatively movable one past the other at a velocity of from 200 to 500 feet per second, whereby the solvent is washed through the fibers of the solid and an extract of material obtained, the velocity of movement of the surfaces past each other and the thickness of the film being such that the solid is not disintegrated to any substantial extent.

19. A method of obtaining an extract from a solid substance comprising, passing the solid substance, together with a suitable solvent of the material to be extracted, in a thin film between smooth, equi-distantly spaced surfaces relatively movable one past the other at a speed of from 200 to 500 feet a second, said surfaces being spaced apart a distance not greater than thirty one thousandths ($\frac{3}{1000}$) of an inch, whereby the solvent is washed through the fibers of the solid and an extract of material obtained, the velocities of movement of the surfaces past each other and the thickness of the film being such that the solid is not disintegrated to any substantial extent.

20. A method of obtaining an extract from a solid substance comprising, passing the comminuted solid substance, together with a suitable solvent of the material to be extracted, in a thin film between smooth, equi-distantly spaced surfaces separated a distance not greater than thirty one thousandths ($\frac{3}{1000}$) of an inch, the size of the comminuted solid particles being not greater than the spacing of these surfaces, said surfaces being relatively movable one past the other at a velocity of from 200 to 500 feet a second, whereby the solvent is washed through the fibers of the solid and an extract of material obtained, the velocity of movement of the surfaces past each other and the thickness of the film being such that the solid is not disintegrated to any substantial extent.

21. A method of obtaining an extract from relatively soft solid substances com-

prising, passing the comminuted solid substances, together with a suitable solvent of the material to be extracted, in a thin film between smooth, equi-distantly spaced surfaces separated a distance not exceeding thirty one thousandths ($\frac{1}{1000}$) of an inch, which may be less than the size of the particles, said surfaces being relatively movable one past the other at a velocity of from 200 to 500 feet per second, whereby the solvent is washed through the fibers of the solid and an extract of material obtained, the velocity of movement of the surfaces past each other and the thickness of the film being such that the solid is not disintegrated to any substantial extent.

22. A method of obtaining an extract from a solid substance comprising passing the comminuted solid substance, together with a suitable solvent of material to be extracted, in a thin film between surfaces separated by a distance equal to the size of the comminuted solid particles relatively movable one past the other at high velocity,

whereby the solvent is washed through the 25 fibers of the solid and an extract of material obtained, the velocity of movement of the surfaces past each other and the thickness of the film being such that the solid is not wholly disintegrated. 30

23. A method of obtaining an extract from a solid substance comprising passing the comminuted solid substance, together with a suitable solvent of the material to be extracted, in a thin film between surfaces 35 separated by a distance equal to the size of the comminuted solid particles, and relatively movable one past the other at high velocity, whereby the solvent is washed through the fibers of the solid and an extract of material obtained, the velocity of the movement of the surfaces past each other and the thickness of the film being such that the solid is not disintegrated to any substantial extent. 40

In testimony whereof I affix my signature.

FREDERICK JOHN EDWIN CHINA.
